VOTING MACHINE

Alvin N. Gustavson, Jamestown, N. Y., assignor to
 Automatic Voting Machine Corporation, a corporation of Delaware

Application April 25, 1932, Serial No. 607,284

2 Claims. (Cl. 235—130)

This invention relates to an improvement in voting machines and more particularly to an arrangement for locking the counter compartment thereof when the machine is in use.

5 One of the prerequisites to universal adoption of voting machines is to provide means for controlling access to any of the working parts for the purpose of eliminating any and all unscrupulous recording of votes. This is preferably accomplished by the provision of several locking and/or latching devices, the key for one of which is in the possession of an election officer, that are so mechanically interconnected as to require the release of one lock before a second lock may be operated. It may thus be understood that on every occasion when access is had to the machine counters or other working parts, each of the election officers must be or have been present to operate his specific lock or latch. In this manner 10 the accuracy of an election ballot cannot readily be questioned since not one but several election officers, presumably chosen from different parties, have in a sense guarded the voting machine.

The preferred embodiment of the device 15 discloses a locking mechanism mounted in a voting machine which is adapted to safeguard examination of the counters during an election by requiring the presence of at least one election official having key controlled access to other parts of 20 the machine.

The principal object of the invention is to provide a device in a voting machine which will render the machine adaptable for use in a larger number of localities where compliance with voting codes 25 and regulations is required.

Another object of the invention is to provide a latch mechanism in a voting machine which requires manipulation of one or more locks before it can be operated.

40 A further object of the invention lies in the provision of the arrangement in a voting machine which will prevent unauthorized examinations of the counters during an election.

A still further object of the invention is to provide a device in a voting machine which will prevent any person from examining the counters during an election unless certain election officers have had knowledge of or are present during that examination.

45 Another and further object of the invention lies in the provision of a latch for the counter compartment of a voting machine which, when released, prevents the unlocking of the entire machine until the compartment is again closed and 50 latched.

Other and further objects of the invention will be more clearly understood from a consideration of the following specification which is taken in conjunction with the accompanying drawing, and in which

Fig. 1 is a fragmentary elevation of the rear of 5 a voting machine showing the principal parts of the invention and their relationship to each other;

Fig. 2 is a vertical sectional view, through the lock, and is taken substantially on the line 2—2 of 10 Figure 1;

Fig. 3 is an elevation of a part of the device which locks or unlocks the operating lever;

Fig. 4 shows a sectional plan view, taken substantially on the line 4—4 of Figure 3; 15

Fig. 5 is a vertical sectional view taken substantially on the line 5—5 of Figure 1;

Fig. 6 is an elevation of one position of the counter compartment latch mechanism;

Fig. 7 shows the other position of the counter 20 latch mechanism;

Fig. 8 is a vertical sectional view taken substantially on the line 8—8 of Figure 7; and

Fig. 9 is a fragmentary plan view, showing the other position of the mechanism shown in Figure 4. 25

Referring to the drawing, and particularly to Figure 1, this invention is shown as forming part of a voting machine, generally indicated by the reference numeral 10. The counter compartment 30 11 is adapted to be concealed from view by a door 12. The lower portion of the door 12 is pivotally joined to the machine 10 in any convenient manner. Rotatably mounted on the upper portion of the door 12 is a knob 13. Secured to the knob 13 35 and projecting from the inner face of the door 12 is a key 14 which is turned by means of the knob. The key is provided with suitable slots 15.

Horizontally mounted between vertical side 40 members 17 and 18 of the machine is a cross-bar 19 which is substantially T-shaped in cross section. A latch 21, welded or otherwise suitably joined to the central portion of the cross bar 19 and having a slotted opening 22 registerable with the key 14, is adapted to retain the door 12 45 in closed position by means of shoulders within the latch 21 which engage with slots 15 in the key. Projecting inwardly from the central portion of the latch 21 is a shaft 23 with a circular plate 24 secured to the end thereof. Openings in the 50 plate 24 are adapted to receive pins 26 and 27 which pivotally support bars 28 and 29 on said plate. The bar 29 is retained in a horizontal position by projecting through a vertical slot 31 in the strip 32. The strip is held in spaced rela- 55

tion to the side of the machine 10 by means of a pair of bolts or pins 33. The free end of the bar 29 projects through the slot 31 and is permitted to slide from one position to another as the plate 24 is rotated. The latch 21 can only be operated subsequent to the manipulation of the entrance knob locking mechanism covered in my Patent No. 1,791,310, which will hereinafter be generally indicated by the reference numeral 34. The entrance knob locking mechanism controls the operating lever and vote indicators and is in turn controlled by a further key controlled lock. A vertical bar 36 of the locking mechanism 34 is provided with a plate 37 having a vertical slot 38 through which one of the bolts or pins 33 projects. The slot 38 in plate 37 permits vertical reciprocation of the bar 36 when the locking mechanism 34 is manipulated. When the counter compartment is locked and the machine is ready for voting, the plate 37 abuts the free end of the bar 29 and prevents the latch 21 from being opened. The voting indicators on the face of the machine are locked against manipulation by operation of the mechanism 34.

25 The bar 28 is twisted one-quarter of a turn and extends in the opposite direction from the bar 29 to the other side of the machine. The extreme end of the bar 28 is joined to a bellcrank 39 which is pivotally supported on a vertical axis by 30 an angle plate 41 mounted on the inner side wall of the machine. The free arm 42 of the bellcrank 39 projects through an opening 43 in a sliding plate 44. Rivets 46 projecting through the side wall of the machine engage slots 47 in the plate 44 and provide support for said plate and permit horizontal reciprocation thereof. Adjacent one end the plate 44 is formed with an offset 48 in which is located the slot 43. The opposite end of the plate 44 is adapted to engage a slot 49 in a vertically reciprocable arm 51, movement of which is caused by the operating lever at the front of the machine. Since the operating lever forms no part of this invention other than to show how the parts connected thereto coordinate with the counter compartment locking device, further description thereof is believed to be unnecessary.

50 Before a person can begin to cast his vote, the custodian in charge of the machine must first unlock the operating lever by lifting the entrance knob which is mounted on one side of the machine. Each voter, upon entering the booth, rotates this operating lever, which is pivoted on the upper edge of the keyboard, from one side 55 of the machine to the other. The movement of the lever draws a curtain around the front of the machine and around the voter and simultaneously unlocks the machine for voting. The latching mechanism for the counter compartment door 60 controls the operation of both the entrance knob and the operating lever. That is, when the counter compartment door is unlatched, the bars 28 and 29 are moved horizontally to actuate certain elements so as to prevent subsequent movement of the entrance knob and the operating lever. The machine is therefore doubly locked against further manipulation when the counter compartment door is unlatched. This arrangement of course doubly insures the machine against 65 any unauthorized person from tampering with the mechanism.

70 With the device in the horizontal position shown in Figures 1 and 6, door 12 of the counter

compartment is locked in closed position. The extreme end of the bar 29 abuts the plate 37, which prevents the door 12 from being unlatched and opened. As soon as the mechanism 34 is manipulated, however, the plate 37 drops to a 5 position such that the upper edge thereof lies slightly beneath the lower edge of the bar 29 (see Figure 7). The knob 13 may now be turned to unlatch the door 12. Rotation of the knob and key 14 causes the bar 29 to move into position 10 over the top edge of the plate 37 and thus prevent manipulation of the locking mechanism 34. The bar 28 is also extended and simultaneously causes the bell crank 39 to rotate slightly. The arm 42 on the bellcrank pushes the end of the plate 44 15 into the slot 49 of the arm 51, thus locking the operating lever and vote indicators against operation.

20 Before the machine can be again operated, it is first necessary to close and lock the counter compartment. As the key 14 is turned in the latch 21, the plate 24 rotates to withdraw the bar 29, thus permitting the locking mechanism 34 to be manipulated. The plate 37 of the locking mechanism 34 is moved upwardly and abuts the extreme 25 end of the bar 29, thus preventing the counter compartment from again being opened until the plate 37 is withdrawn from the end of the bar 29. As the plate 24 rotates the bar 28 is withdrawn which retracts the plate 44 from the 30 slot 49 in the arm 51 and releases the operating arm at the front of the machine.

35 Although applicant has shown and described but one modification of the invention, he does not intend to be limited thereto since it is obvious that other modifications or adaptations of the invention may be made without departing from the spirit and scope of the invention as defined in the hereunto annexed claims.

40 Having thus set forth my invention what I claim as new and for which I desire protection by Letters Patent is:

45 1. In a voting machine having an entrance knob locking mechanism, a counter compartment, a door closing said compartment, a latch on said machine for releasably securing said door in closed position, a latch operating knob on said door, a laterally reciprocable bar joined to and movable with said latch, vertically movable means on said entrance knob locking mechanism abutting 50 said reciprocable bar, said means, when said door latch is in released position, being adapted to prevent manipulation of said entrance knob locking mechanism.

55 2. In a voting machine having an entrance knob locking mechanism, a counter compartment, a door closing said compartment, a latch on said machine for releasably securing said door in closed position, said latch including a knob mounted on said door, a key projecting inwardly 60 from and rotatable with said knob, said key being engageable with a portion of said latch joined to said machine, a laterally reciprocable bar joined to and movable with said latch, vertically movable means on said locking mechanism abutting said reciprocable bar, said means lying in the path of said reciprocable bar for the purpose 65 of preventing manipulation of said door latch without first manipulating said entrance knob locking mechanism to withdraw said means from 70 the path of said reciprocable bar.

ALVIN N. GUSTAVSON.
